ATTORNEYS

UNITED STATES PATENT OFFICE.

ROBERT LANDAU, OF VIENNA, AUSTRIA.

CAP-SHAPED CONTRIVANCE FOR CLOSING VESSELS OR RECEPTACLES.

Application filed October 20, 1927, Serial No. 227,474, and in Austria October 22, 1926.

This invention relates to improvements in cap-shaped contrivances for closing vessels or receptacles, which consist of an elastic material which can be used any number of times.

Known closing contrivances of this kind are provided with a jagged flange rim, the contracted parts of which engage a depression of the bottle neck and are temporarily deformed. Other closing contrivances are known in which depressions, for instance buttons or grooves, provided on the cylindric flange of the contrivance cooperate with suitable rests, or with a contraction 15 of the bottle neck, or directly rest on the smooth bottle neck.

The present invention relates to a cap-shaped contrivance for closing vessels or receptacles and essentially consists in that 20 the flange of the contrivance is divided into resilient curved parts by means of one or more rests, for instance knobs, projections, grooves or the like, the said resilient curved parts being stretched within the limit of elasticity during the application of the contrivance to the smooth neck of the vessel or receptacle and thereby are pressed on to the said neck.

One mode of carrying out the present 30 invention is illustrated by way of example on the accompanying sheet of drawings in which—

Figs. 1, 2 and 3 show in sectional elevation, plan view and cross-sectional view, 35 respectively, a closing contrivance attached to a vessel.

Figs. 4 and 5 show in section and plan view, respectively, a tool for disengaging the closing contrivance according to the first 40 construction.

The closing contrivance for vessels or receptacles consists of a cap formed by a bottom portion α and a cylindric flange b . The diameter of the latter is slightly larger than the outside diameter of the thickened 45 part of the neck d of the bottle c , as it is indicated in dotted lines in Fig. 3. The flange b of the cap is furnished with inwardly directed depressions e , which are 50 in the shape of knobs or projections and are arranged at equal distances apart around the circumference of the said flange or which are in the form of circumferential grooves. An oil paper or parchment paper 55 f and a cork disc g are arranged below the

bottom α of the cap, in order to provide for an air-tight or gas-tight closure. The rim h of the cap is drawn inward and firmly grips the thickened part d of the bottle c in the operative position.

The closing contrivance is attached to and removed from the bottle in the following manner:—

The contrivance is loosely placed upon the mouth of the bottles c and, by means of a blow or pressure applied to the bottom α of the cap, is pushed so far down the thickened bottle part d until the rim h of the cap is disposed in the reduced part of the bottle c behind the said thickened part. The contrivance is already gas-tightly secured to the bottle c by this simple operation. Before pushing down the contrivance, the distance between each pair of diametrically opposite depressions e is smaller than the diameter of the thickened part d , and on pushing down the contrivance the depressions e are radially pressed apart, whereby the parts of the side wall, located between the depressions, are pressed against the part d of the bottle, as shown in Fig. 3. This deformation which takes place in a transverse direction of the contrivance causes a further deformation along the circumference of the flange b , in that the contracted cap edge h resting in the reduced part of the receptacle c is pressed with a greater force against the receptacle owing to the stretching of the apex of the flange b . The reduced or drawn-in border h of the cap insures that the insertions f and g are tightly pressed against the mouth of the bottle.

The tool, illustrated in Figs. 4 and 5, is preferably used for disengaging the closing contrivance. The former consists of a strip 95 or handle k , which is provided with a hole i . The strip or handle is placed over the neck of the bottle in such a manner that the straight edge l of the handle hole i bears against and is supported by the stepped portion m of the vessel c , while the curved edge n of the handle hole i rests against the underside of the cap rim h . The closing contrivance can be readily lifted off by an upward directed pressure, applied by 100 grasping the handle portion o of the strip, and now the contrivance again takes up its original shape.

I claim—

1. A cap-shaped contrivance of an elastic 110

material for closing receptacles, including a flange provided with a plurality of projections widely spaced apart to divide said flange into a number of resilient curved parts 5 which, during the application of the contrivance to the neck of a receptacle, are stretched, whereby the middle portion of each curved part is pressed on to said neck.

2. A cap-shaped contrivance for closing 10 receptacles, as claimed in claim 1, in which said flange is of the same thickness as the bottom of the cap and is provided with a contracted rim, the flange being circumferentially deformed and also bent through along 15 its generatrix and adapted to have its contracted rim pressed with great force on to the receptacle, whereby the bottom of the cap is bent inward and tightly pressed with great force on to the receptacle.

20 3. A cap-shaped contrivance of an elastic material for closing receptacles, including a

flange provided with a single inwardly extending projection, the place of the remaining resilient curved part of the flange disposed opposite the said projection being 25 pressed on to the neck of a receptacle during the application of the contrivance to the said neck.

4. A cap-shaped contrivance for closing 30 receptacles, as claimed in claim 3, in which said flange is of the same thickness as the bottom of the cap and is provided with a contracted rim, the flange being circumferentially deformed and also bent through along 35 its generatrix and adapted to have its contracted rim pressed with great force on to the receptacle, whereby the bottom of the cap is bent inward and tightly pressed with great force on to the receptacle.

In testimony whereof I have affixed my 40 signature.

ROBERT LANDAU
